UNITED STATES PATENT OFFICE.

IRENE PATTERSON, OF TRINIDAD, COLORADO.

DESIGN FOR A STOCKING.

Application filed November 30, 1926. Serial No. 19,889. Term of patent 3½ years.

To all whom it may concern:

Be it known that I, IRENE PATTERSON, a citizen of the United States, residing at Trinidad, in the county of Las Animas and State of Colorado, have invented a new, original, and ornamental Design for Stockings, of which the following is a specification, reference being had to the accompanying drawing, forming a part thereof.

The figure is a rear view of a stocking embodying my design.

I claim:

The ornamental design for a stocking, as shown.

IRENE PATTERSON.
